SOFT COLLAR

Filed April 22, 1929

UNITED STATES PATENT OFFICE

ISAAC MARINSKY, OF PROVIDENCE, RHODE ISLAND

SOFT COLLAR

Application filed April 22, 1929. Serial No. 356,907.

My invention relates to the type of soft collars which are lined.

The essential objects of my invention are to stiffen the collar along the margins of its adjacent ends and along the line of the fold by a means particularly adapted to the structure of a collar of the lined type, whereby any necessary pocket slit may be located adjacent the line of the fold, and not at a distance therefrom; and to effect this end in a structure involving a minimum of labor and expense.

My invention consists in the means for effecting the results above specified substantially as hereinafter claimed.

In the accompanying drawings which form a part of this specification

Figure 1 is a front view of my invention embodied in a lined soft collar,

Figure 2, a fragmentary rear view of the same, the neck band being shown elevated,

Figure 3, a section taken on line 3—3 of Figure 2,

Figure 4, a rear view of the stiffening member removed, and

Figure 5, a fragmentary reverse view of the same.

Similar characters of reference indicate similar parts throughout the views.

The collar herein shown comprises a soft neckband 7 and soft flap 8, the latter terminating in diverging points 9, and a fold 10.

The neckband is composed of a foundation or base strip 12, a lining strip 13, and a facing strip 14, all of soft fabric, and the strip 14 being preferably of silk. The flap comprises a foundation or base strip 16, a lining strip 17, and a facing strip 18 of the same materials respectively as the strips of the neckband.

The flap strips are bound together along their end edges 19 and bottom edges 20 by concealed lines of stitches 23 and 24 respectively, and equispaced therefrom are end marginal lines of stitches 26 and a bottom marginal line of stitches 27. The edge lines of stitches 23 and the marginal lines of stitches 26 adjacent thereto and parallel therewith, combine with the narrow upwardly inclined spaces 28 between the lining strip and base strip to form pockets 29 whose

mouths 30 extend along the collar fold 10. Each pocket has its upper edge defined by an inturned fold 32 formed by making two vertical spaced parallel slits downwardly from the upper edge of the lining strip 17 and then downwardly folding the slit material. This folded edge prevents the top of the pocket from fraying by wear or laundering.

After the edge of the pocket is folded the flap is attached to the neck band by inserting its upper edge between the foundation strip 12 and the facing strip 14 of the band a short distance, the facing strip 14, overlapping the lining strip 17. The lower edges of all the neck band strips are upwardly folded inwardly, and their upper edges are downwardly folded inwardly. The parts thus positioned are bound together by spaced lines of stitches 36 extending along the lower margin of the neck band, continuous with similar lines of stitches 38 extending along the upper margin of the same. The band 7 is provided as usual with end button holes 40 and an intermediate button hole 41. In folding the collar for use the band is turned downward in the direction of the arrow shown in Figure 3 with its facing strip 14 adjacent the lining strip 17 of the flap.

Before folding however removable stiffening elements 43 of the collar are introduced into the pockets. The stiffening members are of stiff material having a degree of pliability such as thin sheet metal, although celluloid may be used less advantageously. Each stiffening member is formed of flat stock and comprises a vertically inclined arm 44 having upon its upper end an open rearwardly and downwardly directed fold or arched neck portion 45, the line of the fold being disposed at an obtuse angle to the arm 44. Continuous with the lower end of the yoke or fold 45 is a substantially horizontal arm 47, disposed at an obtuse angle to the arm 44 and lying in a parallel plane thereto and spaced therefrom. The arms 44 are slidably inserted in the pockets 29 with the arches or necks 45 enclosing the upper margins of the pockets, the upper edges of the arms 47 following along the line of the fold 10.

The necks 45 of the stiffening members 43

are important in that they enable the mouths 30 of the pockets to be located along the junction of the flap and the collar band where the general collar construction lends itself to the facile and concealed construction of the folds

5 32. Furthermore, the location of the pocket mouth at a point substantially below the plane of the fold would increase the difficulty and expense and the mutilated portions of the lining strip 17 would be exposed in certain 10 positions of the flap.

It should be noted that in this lined soft collar the portions of the lines of stitches 23 which extend along the collar end edges 19,

15 and the lines of stitches 26 parallel thereto which are requisite in the ordinary construction of lined soft collars are herein utilized as a part of the pocket construction also, which is a saving of expense over that of specially constructed pockets located elsewhere 20 in the flap.

It will be observed that the stiffening member by reason of the offset character of the portion 45 is particularly adapted to facile insertion and removal into and from its marginal pocket.

I claim:—

1. In a lined soft collar, a neck band, a flap comprising a foundation strip and a lining 30 strip attached thereto, a fold along the top of the flap, upwardly directed pockets in the lining provided with mouths disposed along the fold, and stiffening members comprising arms slidably mounted in the pockets, vertical folds upon the upper ends of the arms 35 located in the mouths of the pockets, and arms integral with the lower ends of the folds exterior of the pockets and disposed along the fold at an angle to the first arms.

40 2. In a lined soft collar, a neck band, a flap comprising a foundation strip and a lining strip attached at their upper edges to the neck band and attached together along their end edges by edge lines of stitches, and along their 45 end margins by marginal lines of stitches forming upwardly inclined pockets between the strips, a fold along the top of the flap, and stiffening members comprising arms in the pockets slidably mounted in the pockets, 50 downwardly directed folds upon the upper ends of the arms extending exterior of the pockets, and arms disposed at an angle to the first arms integral with the second fold and extending along the first mentioned fold.

55 In testimony whereof I have affixed my signature.

ISAAC MARINSKY.
